UNITED STATES PATENT OFFICE.

WILLIAM E. WOODARD, OF FOREST HILLS, NEW YORK.

CAR TRUCK.

Application filed January 7, 1922. Serial No. 527,555.

To all whom it may concern:

Be it known that I, WILLIAM E. WOODARD, a citizen of the United States, residing at Forest Hills, in the county of Queens 5 and State of New York, have invented certain new and useful Improvements in Car Trucks, of which the following is a specification.

This invention relates to car trucks and 10 is particularly useful in connection with that class of car truck in which the weight of the car body is supported upon a bolster which in turn rests upon springs and spring planks, the latter of which are supported 15 from the truck structure by means of links.

One of the primary objects of my invention is to provide a simple and effective means whereby the height of the truck bolster may be readily adjusted in order to 20 bring the platform of a car carried thereon to the level of adjacent platforms or to vary the height of couplers or steps.

Another of the objects of my invention is the provision of means of the character described 25 which are suitable to the heavier construction of trucks now in use.

Among the more specific objects of my invention is the provision of an inexpensive means for varying the height of the truck 30 which may be adjusted very readily.

I accomplish the foregoing, together with such other objects as may hereinafter appear, or are incident to my invention, by means of a construction which I have illustrated in preferred form in the accompanying drawings, wherein:

Fig. 1 is a sectional view taken through a four-wheel car truck on the line 1—1 of Fig. 2, illustrating the application of my 40 invention thereto; Fig. 2 is a section taken on the line 2—2 of Fig. 1; Fig. 3 illustrates the manner in which adjustment is effected and also a spring plank embodying some modified features of my invention; Fig. 4 45 is a bottom plan view of a spring plank such as shown in Fig. 3; Fig. 5 is a bottom plan view of the height adjusting means; and Fig. 6 is a diagrammatic plan view of a truck such as shown in Figs. 1 and 2.

Referring now to the figures, only such 50 portions of the truck proper—which may be of any preferred construction—as are necessary to an understanding of the invention will be described. The frame A has 55 transoms 7 between which is a swing or lateral motion bolster 8, the ends of which

rest upon the pairs of semi-elliptic springs 9, which in turn are carried on a novel form of spring plank 10 suspended from the transoms 7 by means of the swing links or 60 hangers 11. Special height adjusting wedge-like members or blocks B are interposed between the lower face of the spring plank 12.

For reasons which will appear in the description of the construction of the spring plank, I prefer to construct the blocks B with three tongues 13. Considered as a whole, each block B is a wedge increasing in thickness from the base portion 14 toward the end of the tongues or forks 13. In the lower face of each block are a plurality of seats 15 which are in stepped relation by virtue of the general construction of the block. 75

The spring planks are flanged at the sides as indicated at 10^a so that in cross section they are channel shaped; and they are further reinforced or strengthened by means of the pairs of spaced, longitudinally extending ribs 10^b. At their outer ends the ribs 10^b depend below the flanges 10^a to provide the "jacking spots" 10^c in Figs. 2, 3 and 4. They have the additional function, in the construction shown in Fig. 2, of 80 preventing inward movement of the lower ends of the swing links.

It will be apparent from the foregoing that the height of the bolster depends upon the position of the adjusting wedges B. 90 When it is desired to adjust the height of the truck bolster, the car is preferably placed over a pit so that jacks can be placed under the "jacking spots" of the spring plank. On raising the jacks the spring 95 plank with the parts supported thereon are elevated, thus leaving the swing links free although still maintained in substantially proper position by the projecting jacking spots. When the spring plank is raised 100 sufficiently to relieve the swing links of weight, the adjustable blocks are placed in a position corresponding with the height required, the jacks are lowered and the car is ready for service. 105

By making the adjusting blocks of the construction shown they are accommodated to the peculiar construction of the spring plank without impairing the strength of the latter. At the same time relative displacement of the blocks laterally with respect to the plank is prevented. 110

As another means for positioning the adjusting blocks relative to the spring plank, the blocks and the spring plank may be provided with interengaging means such as the lugs 20 and the pockets 21 (see Figs. 3, 4 and 5). As there shown, the lugs 20 are formed on the spring plank and the recesses 21 are formed in the upper face of the adjusting blocks, one being opposite each of the seats 15.

What I claim is:

1. In a car truck, the combination of a frame, a lateral motion bolster, swing hangers by which said bolster is suspended from the frame, and adjusting blocks between the swing hangers and the bolster, each of said blocks being provided with a plurality of stepped seats and the blocks being adjustable by movement toward and away from each other longitudinally of the bolster.

2. In a car truck, the combination of a frame, a lateral motion bolster, a spring plank on which said bolster is spring supported, swing hangers by which said spring plank is suspended from the frame, and adjusting blocks interposed between the swing hangers and the spring plank, said adjusting blocks being provided with a plurality of stepped seats and being adjustable on movement toward or away from each other longitudinally of the spring plank.

3. In a car truck, the combination of a frame, a lateral motion bolster, a spring plank on which said bolster is spring supported, swing hangers by which said spring plank is suspended from the frame, and adjusting blocks interposed between the swing hangers and the spring plank, said adjusting blocks being provided with a plurality of stepped seats and being adjustable on movement toward or away from each other longitudinally of the spring plank, together with interengaging means on the spring plank and adjusting blocks whereby the latter are held in positions of adjustment.

4. An adjusting block for truck swing hangers of a general wedge shape and provided with a plurality of swing link or hanger seats.

5. In a car truck, the combination of a frame a lateral motion bolster, swing hangers by which said bolster is suspended from the frame, and incline plane means to vary the vertical relation of the parts.

6. An adjusting block for truck swing hangers having a plurality of swing hanger or link seats arranged in stepped relation and so disposed that when the block is shifted bodily in a plane transverse the swing links, a different seat is presented.

7. In a car truck, the combination of a frame, a lateral motion bolster, swing hangers by which said bolster is suspended from the frame, and adjusting blocks between the swing hangers and the bolster, said blocks being wedge shaped and adjustable on movement toward or away from each other.

8. In a truck, the combination of a frame, a spring supported bolster a spring plank, swing links for supporting the plank, and jacking spots on the plank which act to position the links when the load is released.

9. In a truck, the combination of a frame, a spring supported bolster, a spring plank of channel shape in cross section, swing links for supporting the plank, and a jacking spot near each end of the plank, said spots acting to position the links when the load is released.

10. In a truck, the combination of a frame, a bolster, a plank of channel cross section for supporting said bolster and having a reinforcing in the web, and adjustment blocks for varying the height of the bolster, said reinforcing acting as a guide for the adjustment blocks.

11. In a truck, the combination of a frame, a bolster, a plank of channel cross section for supporting said bolster and having a reinforcing in the web, at each end extending longitudinally of the plank, and adjustment blocks for varying the height of the bolster, said reinforcing acting as a guide for the adjustment blocks.

12. In a car truck, the combination of a frame, a lateral motion bolster a spring plank, swing hangers, wedging means between the spring plank and hangers, and means for positioning the swing links.

In testimony whereof, I have hereunto signed my name,

WILLIAM E. WOODARD.
